UNITED STATES PATENT OFFICE.

LUTHER C. CROWELL, OF BROOKLYN, ASSIGNOR TO R. HOE & CO., OF NEW YORK, N. Y.

FOLDING AND WRAPPING MACHINE.

SPECIFICATION forming part of Letters Patent No. 269,185, dated December 19, 1882.

Application filed February 1, 1882. (No model.)

To all whom it may concern:

Be it known that I, LUTHER C. CROWELL, a citizen of the United States, residing in the city of Brooklyn, county of Kings, and State of New York, have invented certain new and useful Improvements in Folding and Wrapping Machines, fully described and represented in the following specification and the accompanying drawings, forming a part of the same.

10 In newspaper printing, as it is conducted at the present time, it is often desirable to have an edition or issue delivered from the printing mechanism in two different forms—that is to say, one part in suitable form for carriers or street or counter sale, and the rest in form for mailing.

This invention relates to a folding and delivering mechanism designed to accomplish this object.

20 To this end it consists in a mechanism constructed and arranged to give the final folds to the sheets and wrap and deliver them into the packing-box in proper form for mailing, which mechanism is also so arranged that a portion of it can be made inoperative and that the other portion will then operate to deliver the sheets with a less number of folds and in suitable form for carriers or street or counter sale.

25 It also consists in an improved folding mechanism, and in certain details of construction and combinations of parts, all of which will be hereinafter fully described, and pointed out in detail.

30 In said drawings, Figure 1 is a plan view of a mechanism embodying my invention. Fig. 2 is a longitudinal vertical section of the same, taken on the line $x-x$ of Fig. 1. Fig. 3 is a longitudinal horizontal section of the same mechanism, but showing in addition the web of wrapping-paper. Fig. 4 is a detached view of the first blade-carrying roll and its companion, showing also the mechanism for making the folding-blade inoperative. Figs. 5, 6, 40 7, 8, 9, and 10 are sectional views showing the first folding-blade in various positions. Fig. 11 is a plan view of the gearing which drives the first folding-blade. Figs. 12, 13, 14, and 45 15 are sectional views, showing the third blade-

50 roll and its companion with the blade in different positions, also showing a device for pasting the wrapper and means for severing the wrappers from the web. Fig. 16 is a side view of the third blade-carrying roll and its companion, and showing also the gearing by which the blade is driven. Fig. 17 is a sectional detail taken on the line $x-x$ of Fig. 4; and Fig. 18 is a modification showing the folding-blade as reciprocated.

55 The printed sheets, before being delivered to the mechanism shown in the accompanying drawings and about to be described, are operated upon by any approved form of folding mechanism, so as to be reduced to a form or size suitable for the carrier or for street or counter sale.

60 Folding mechanisms adapted to bring sheets to this size or form are well known in the art, and need no specific description here. If a single longitudinal fold is sufficient to reduce 70 the sheet or associated sheets to the required size, then the result can be well attained by passing the sheet or sheets over a folder of the form shown in United States Letters Patent No. 233,996. If, in addition to the longitudinal fold, it is desired to fold the sheet or sheets 75 transversely, then an ordinary rotary folder, or a rotary folder of the construction about to be described, may be located so as to operate upon the sheets, either before they pass to or 80 after they pass from the longitudinal folder. The sheet or associated sheets, having been folded so as to be reduced to a size suitable for the carrier or street sale, pass away from the end 1 of the longitudinal folder, (see Fig. 1,) 85 or other folding mechanism and into the bite of the rolls 2 3.

85 In Fig. 1 there are shown portions of the tapes 4 5 6, which convey the sheets over the longitudinal folder. The tapes 4 and 5 are in 90 this case shown as passing around the rolls 2 and 3, respectively, and thence back around one or more pulleys (not shown) to the starting-point. This arrangement of the tapes has been found a very good one, as it tends to insure the even and prompt delivery of the sheets to the rolls 2 3; but it is not essential. The tapes may pass around the rolls 2 3, or they

may stop short of these rolls, and, passing over pulleys, as shown with respect to tape 6, return, leaving the sheet to be projected between guides and into the bite of the rolls. The rolls 2 3 are connected by gears 7 8 upon the upper ends of their shafts, through which, by connection with any convenient source of power, these rolls are positively and continuously driven, their surface-speed being of course just 10 equal to the feed of the sheet over the longitudinal folder.

It has been found that by the use of a folding-blade, constructed and operated as herein-after described, rolls of much smaller size than 15 those heretofore used can be made available in this position, and as it is desirable to make the apparatus as compact and economical as possible the rolls 2 3 are in the present case so reduced in size that they are required to 20 make two complete revolutions during the passage of each sheet between them.

Upon the shaft of roll 2, just above gear 7, is mounted the small gear 9, which meshes with an intermediate gear, 10, through which the 25 mechanism for making the final fold and wrapping and delivering the sheet is driven, as will be hereinafter fully explained. This gear 9 is mounted loosely upon its shaft, but is arranged to be made fast to the face of gear 7 by means 30 of the screw 11, or by some convenient form of clutch mechanism.

If it is desired to deliver the papers folded and wrapped in proper form for mailing, the sheets will, as they emerge from rolls 2 3, be 35 operated upon by mechanism now to be described.

The roll 3 has formed in one of its sides a series of recesses, 12, cut to a sufficient depth to allow the passage of the sections 13 of a rotating folding-blade. The portions of the roll 40 between the recesses are left substantially intact, so that sufficient surface remains to insure the even feeding of the sheet between this roll and its companion.

45 The ends of roll 3 are provided with rims or projections 14, (in Figs. 2 and 4 rims are shown, in the other figures simple projections, these constructions being considered full equivalents,) in which is journaled the shaft 15, 50 which is partially sunk in a groove in the periphery of the roll outside of the recesses 12, and which carries the sections 13, forming the folding-blade. The shaft 15 is shown as journaled so that one-half of its diameter only is 55 within the periphery of roll 3, roll 2 being provided with a groove, 89, to permit the passage of the shaft between the rolls. It is not essential, however, that it should be located in this exact position. It may lie wholly without or 60 wholly within, or be sunk slightly below the periphery of roll 3.

As before stated, the rolls 2 3 are of such size that they are required to make two complete revolutions during the passage of each sheet 65 between them. The folding-blade 13 is therefore required to act only at each second revolution of its carrying-roll. It may, however,

be so actuated as to be brought into operative position at each revolution of the roll 3, in which case its alternate strokes will be idle, its 70 edge passing to the bite of the folding-rolls just in advance of the leading end of the sheet, and of course having nothing to operate upon. It is, however, most desirable that the blade should not make such idle strokes, and 75 consequently it is shown as driven so as to be brought into operative position only at each second revolution of its carrying-roll. This is effected by the following mechanism: The shaft 18 is extended beyond the end of roll 3, and is 80 provided with two sleeves, 16 and 17, the ends of which meet. The sleeve 16 is loose upon the shaft, but is rigidly attached to the frame of the machine. The adjoining ends of these sleeves are provided with coinciding slots 19 85 20, the slot 19 containing the sliding key 21, and the slot 20 the spring-catch 22. This spring-catch is secured to sleeve 17, so that when in its normal position it projects inward through the slot 20 and takes into a recess, 23, in the 90 shaft 18, so that the sleeve 17 is locked to the shaft. The sliding key 21 when in its normal position rests entirely within the slot 19; but it is provided upon its outer edge with a rack, which engages with the segment 24 upon the 95 rock-shaft 25, so that when the latter is operated, which may be done by a handle placed in any convenient position, the key will be moved, so as to project beyond the slot 19 and into the slot 20, its projecting end, which is 100 wedge-shaped, as shown, operating to raise the spring-catch 22 out of the recess 23, thus releasing the sleeve 17 from the shaft 18, and at the same time locking sleeves 16 and 17 together. When the sleeves are thus locked the 105 gear 26, secured to the upper end of sleeve 17, becomes stationary and operates to rotate the folding-blade 13, as will presently appear. This gear engages with a gear, 27, of equal size, which is fixed to the short shaft 28, having its 110 bearings in the end of roll 3 and in a plate, 29, secured to the ends of posts 30, projecting from the end of the said roll.

The end of the shaft 15 of the folding-blade 115 extends through and beyond the rim or projection 14 and has a bearing in the plate 29. This extension of the shaft is provided with a gear, 31, of equal size with the gears 26 and 27, which is held loosely between collars 32 33, which are fast upon the shaft. The collar 32 is cut away 120 for a portion of its length upon one side, so as to form a circumferential recess, 34, of considerable extent. The hub of gear 31 is provided with a projection, 35, which extends into the recess 34, so that the gear and shaft 15 125 will rotate together. The recess 34 is, however, of such size with relation to the projection 35 that, for a purpose to be presently explained, considerable play or lost motion is allowed. The shaft 15 and gear 31 may be connected by a spiral spring, 99, (see Fig. 2,) the tendency of which is to hold the edge 98 of projection 35 against edge 97 of collar 32, and 130 to return the parts to that position when they

have been forced apart. The spring 99 is not, however, essential, as the devices will be operated when it is omitted, as in Fig. 4. In addition to the gear 27 the shaft 28 is also provided with a gear, 36, of one-half the other's size, which engages with and drives gear 31.

It will thus be readily seen that when the sleeves 16 and 17 are locked together by the key 21 the devices just described will operate, during two complete revolutions of the roll 3, to revolve the blade 13 once and in a direction opposite to that of the revolutions of the roll.

As before stated, the rolls 2 3 are of such size that they are required to make two complete revolutions during the passage of each sheet between them, and the folding-blade 13 is so driven as to be brought into operative position at every second revolution of its carrying-roll 3. The blade, rotating as it does in a direction opposite to that of roll 3 is so timed that as the fold-line of the sheet arrives at the point of contact between rolls 2 and 3 its edge passes outside the periphery of roll 3 and presses the sheet upon the fold-line against the surface of roll 2, as shown in Fig. 5. During this part of its revolution upon its own axis the edge of the blade will be carried farther and farther beyond the periphery of the roll 3, so that it will continue to press the sheet against roll 2, and as the blade is carried bodily onward by roll 3 in its revolution the edge of the blade will be permitted to travel onward with the sheet as it moves with roll 2. This outward and onward movement will be continued until just before the parts arrive at the positions shown in Fig. 6, at which point the blade will force the fold-line of the sheet into the bite of rolls 2 and 37, immediately after which roll 3 will, in its onward rotation, withdraw the blade and carry it rapidly away from roll 2, as shown in Fig. 6.

It will be observed that the blade 13 is curved in the direction of its width, which is an important feature of the construction, no other form being capable of operating in the manner described. This is quite evident from the fact that its edge must follow and bear against the surface of roll 2 at the same time that its axis (the shaft 15) comes in contact or nearly in contact with the same roll.

Although the blade 13 makes just one complete revolution on its axis while the roll 3 is making two, its speed, as will be noted, is quite different in different parts of its revolution—55 at one point being accelerated, at another retarded, and at another entirely checked. This variation of speed is permitted by the play or lost motion which the gear 31 has upon the shaft 15, as heretofore explained, and is caused by the cam 38 upon the end of roll 2, (shown in Fig. 2, and in dotted lines in Figs. 5, 8, 9, and 10,) and by the fixed cam 39, (best shown in Figs. 2, 3, and 5.)

During the first one-fourth or a trifle more, 65 of a revolution of the roll 3 from the position shown in Fig. 5, the speed of the blade 13 around its axis must be considerably accelerated

in order to keep its folding-edge upon the surface of roll 2. This acceleration is effected by the side 40 of cam 38, upon which the bowl 41 of the arm 42, carried by the shaft 15 of the folding-blade, strikes just after the rolls pass the position shown in Fig. 5. The rolls 2 and 3 being rotated at the same speed, it follows that the shaft 15 of the folding-blade and the point of cam surface 40 at the periphery of roll 2 move with the same velocity, but the bowl 41, being at this time considerably outside the periphery of roll 3, is moving with a velocity much greater than that of the surfaces 80 of the rolls, and consequently of the cam-surface 40. As soon, however, as the bowl enters within the periphery of roll 2 and strikes upon cam 40 it will be held back and permitted to advance only at a speed equal to that of the 85 cam, which speed will constantly decrease as the bowl passes inward onto the slower-moving portions of the cam. This holding back of the arm 42 draws the blade 13 outward from the roll 3, and advances it in its revolution around its axis 15 at a speed much greater than that with which it would be driven by its train of gearing. The action of cam 40 upon arm 42 will also press and hold the blade 13 tightly against the surface of roll 2 until 95 the fold is made, at which time the bowl 41 will pass onto the side 43 of cam 38, and as this cam-surface will then be moving in a direction contrary to that of the bowl in its revolution around the shaft 15, said shaft and 100 blade will be somewhat retarded. This will continue until the parts reach the position shown in Fig. 6, when a little less than one-half of a revolution will have been accomplished. The bowl 41 will then pass outside 105 the periphery of roll 2 and the blade will resume its normal movements. The positions which the different parts will occupy when the spring 99 is used, when three-fourths, one, and one and one-fourth revolutions have been accomplished, are shown in Figs. 7, 8, and 9, respectively.

Owing to the play or lost motion permitted between shaft 15 and gear 31 the blade during the last part of the second revolution will be 115 thrown forward by the centrifugal force caused by the rapid revolution of roll 3, and the bowl 41 will pass outside the periphery of the roll to the position shown in Fig. 10, where it will be arrested by the cam 39, and from then until 120 the second revolution is completed and the bowl again passes onto cam 38, the blade 13 will have little or no motion around the shaft 15.

From the foregoing it will be seen that the blade 13, when performing its work, is operated and controlled almost entirely by the cams, the function of the gears being mainly to move it during the idle part of its revolution and to bring it into proper position to be operated upon by the cams when required.

The roll 37 has secured to its end the gear 44, which engages with the gear 7 upon the roll 2, so that the two run with the same surface-speed. The sheet having been folded into the

bite of these rolls by the blade 13, as already described, passes between them, and is projected between guides 45, supported by rods 53, until it is caught in the bite of rolls 46 and 47. These rolls are provided upon their ends with engaging-gears 48 49, the latter also engaging with gears 59 and 60, by which they and folding and delivering rolls 56 and 61 are driven from gear 9 through intermediate gear, 10. The rolls 46 47 are of the same size as rolls 2 3, and, owing to the reduced size of the sheets upon which they operate, are required to make but one revolution during the passage of each sheet between them. This permits them to be 15 driven at one-half the speed of the former. Hence the reduced size of gear 9.

As the sheets pass between the rolls 46 47 they are associated with wrappers in the following manner: Upon the horizontal shaft 50, 20 which is mounted in suitable bearings, is placed a roll of wrapping material, the end of which, being conducted over the angularly-arranged turner 51, is introduced between the rolls 46 47 and impaled upon the pins 52, carried by the former. The wrapper will thus be drawn forward and associated with the incoming sheet, the pins 52 serving to hold the leading end of the wrapper and with it the sheet onto the roll 46.

30 It is to be remarked that the sheets before passing between rolls 2 37 will be so accelerated that they will be separated some distance from each other, and also that the rolls 46 47 are of such size that the length of the transversely-folded sheets passing to them is equal to only about three-fourths the circumference of these rolls. These rolls are therefore so timed in their movements that the sheets will enter their bite a short distance behind the 40 pins 52 and the leading end of the wrapper.

In order to afford room for the accumulated thickness of paper contained in the folded sheets, the rolls 46 47 do not run in close contact; but to give the rolls a firm hold upon the 45 leading end of the wrapper and to insure its being impaled upon the pins 52 the roll 47 is, upon that portion of its surface between the leading end of the wrapper and the point where the incoming sheet enters, provided with a 50 projection, 54, formed of rubber or any suitable material, of such thickness as to press tightly against roll 46.

The roll 46, except in particulars specified, is of the same construction as roll 3, and carries a folding-blade, 55, of the same construction and having the same operation and auxiliaries as the blade carried by that roll, except that blade 55 is made to revolve about its axis once for each revolution of its carrying-roll. This difference in speed is effected by making the gear corresponding to 36 of the same size as that corresponding to 31, or by omitting 36 and making the gear corresponding to 27 engage directly with that corresponding to 31.

The wrapper and sheet passing between the rolls 46 47 will be carried by the pins, as al-

ready stated, upon the surface of roll 46 until the fold-line reaches a point directly between the axes of the rolls, at which time the blade 55 will pass outside the periphery of roll 46, and striking the sheet upon the fold-line press it firmly against roll 47, and tearing the end of the wrapper from the pins fold both wrapper and sheet between rolls 47 and 56, in a manner already described. As the sheet and wrapper thus folded pass onward between the rolls 47 56 the rolls 46 47 complete a revolution, when a severing-blade, 57, set in roll 46, cutting into a groove, 58, in roll 47, severs the wrapper from the web, leaving a projecting end for a sealing-flap, as shown, and at the same time the pins 52 impale the fresh end of the web and carry it forward to form a wrapper for the next succeeding sheet. 85

In the operations described the sheet, which was received in a form suitable for the carrier or street sale, has received two parallel transverse folds, which has reduced it to a form suitable for the mail, and has had a wrapper folded around it. It now remains to fold down the projecting ends of the wrapper, seal it, and deliver the product from the machine. 90

As the sheet and wrapper pass between rolls 47 56 a pasting device carried by the latter 95 places a transverse line of paste upon the wrapper at a suitable point to secure the longer of the projecting ends. This pasting device consists of a cylindrical tank, 62, having a narrow opening along one side, and in which is journaled a paste-roll, 63, so positioned that it will close the opening in the side of the tank. This roll is made with a series of longitudinal grooves, in which the paste will be carried through the opening in the tank. This tank 100 is inserted in a recess formed in the side of the roll, so that the projecting surface of the paste-roll 63 will be flush with or project slightly beyond the surface of roll 56. The roll 63, coming in contact with the wrapper, as it and the sheet pass between rolls 47 56, will by the pressure of the package be caused to turn slightly in its bearings, thus bringing out a groove filled with paste, which will be applied in a line to the wrapper, and as each succeeding sheet and wrapper pass a fresh groove will be brought out with the same result. It will 110 of course be understood that when a paste-fountain of this kind is carried in a vertical roll, as in the present case, provision must be 115 made for keeping it constantly filled. This can be done in a variety of ways, as will readily be seen. The roll 56 is of the same construction, except as to the pasting device, as roll 3, and carries a folding-blade, 64, of the 120 same construction and operation, and having the same auxiliaries as blade 55. The roll 56 is, however, so timed that the blade 64 does not strike the sheet, but strikes just in its rear and upon the projecting ends of the wrapper. 125 The result is that the sheet is not folded between rolls 47 61, but that the projecting ends of the wrapper are laid over upon its body, and as the wrapped sheet passes between the 130

135

rolls the longer of the projecting ends is pressed upon the line of paste and secured.

The sheets may be so fed to rolls 46 47 that the second cross-fold will be made a little in advance of their centers, leaving the ends uneven, in which case the longer end may be struck by blade 64 and folded over with the projecting ends of the wrapper, which will tend to make the wrapper more secure.

10 It may be remarked that roll 47 is provided with two cams, corresponding to cam 38—one, 65, to operate blade 64, and another, 66, to operate blade 55. As the wrapped sheet enters the bite of rolls 47 61 its leading end is caught by the grippers 67, which are constructed and operated in the usual manner and carried around until in a position opposite the end of the packing-box 68, when it is released and pushed into the box by the enlargement 69 on

20 the roll 61.

The operations of the folding-blade 64 and pasting device are well shown in Figs. 12 to 15, inclusive, in which Fig. 12 shows the position of the parts at the time the line of paste 25 is being applied to the wrapper; Fig. 13, at the time the wrapper is being severed from the web and the blade is just pressing the projecting ends of the wrapper against roll 47; Fig. 14, at the time the blade is folding the projecting ends of the wrapper into the bite of rolls 47 61, and Fig. 15 just before the fold is made.

If it should be desired to fold the sheet more than once transversely before placing the wrapper around it, the roll 37 may be provided with 35 a folding-blade of the same construction as those in rolls 3, 46, and 56, which will operate to fold the sheet between the rolls 2 and a companion, which can be provided, after which the sheet will be conducted to rolls 46 47 to 40 receive the final fold and the wrapper.

When it is desired to deliver the sheets unwrapped and in a form suitable for the carrier, the gear 9 is rendered idle by the withdrawal of the screw 11, and the rock-shaft 25 is operated to withdraw the key 21 from slot 20, which disconnects the sleeves 16 17 and renders the folding-blade 13 inoperative, and allows the catch 22 to pass into the recess 23, locking the blade inside its roll in the position shown in 45 Fig. 4. The sheets will then pass outward between guides 75 76 and be taken by any appropriate form of delivery mechanism. A mechanism especially well adapted for this purpose forms the subject-matter of an application which I am about to file in the United 50 States Patent Office.

Although the machine here shown is arranged to operate upon the sheet while in a vertical position, this arrangement is not essential. It may be readily so positioned as to receive, fold, and deliver horizontally.

In Fig. 18 a modified construction is shown, in which the folding-blade, instead of being mounted upon a rotating carrier and itself having a rotating motion, is mounted upon a reciprocating carrier and given an oscillating motion. The curved blade 13 is pivoted in any conven-

ient manner to the end of the carrier 100, which carrier is reciprocated by any suitable means. Rigidly attached to the back of the blade is 70 the arm 101, provided at its outer end with the bowl 102, which travels in the cam-groove 103. As the blade is advanced from the retracted position shown by the dotted lines the cam 103, acting upon the bowl 102, will depress the folding-edge of the blade and cause it to press the paper upon the fold-line against the surface of roll 2, and as the blade and roll advance together the cam will cause the edge of the blade to follow the curvature of the roll, 80 pressing the fold-line of the sheet snugly against it until the bite of the folding-roll is reached and the fold is made, as is shown in the figure. The motion of the carrier 100 being reversed at this point, the blade will be withdrawn and 85 returned to repeat the operation.

A mechanism embodying the construction just described will form the subject-matter of a future application for United States Letters Patent.

What I claim is—

1. A pair of folding-rolls, as 2 37, in combination with an irregularly-rotated folding-blade, as 13, curved in cross-section, substantially as described.

2. A roll, as 2, in combination with an irregularly-rotated folding-blade, as 13, so timed in its rotations that its folding-edge presses the sheet upon the fold-line against the surface of said roll, and moves forward with said sheet 100 and surface until the fold is made, substantially as described.

3. A roll, as 2, in combination with a curved folding-blade, so timed in its movements that its folding-edge presses the sheet upon the 105 fold-line against the surface of said roll, and moves forward with said sheet and surface until the fold is made, substantially as described.

4. The combination, with a pair of folding-rolls, of a curved folding-blade, the edge of 110 which presses the fold-line of the sheet against one of the folding-rolls and then moves onward with the sheet and roll until the fold is made, substantially as described.

5. The combination of a pair of folding-rolls 115 and a rotating blade-roll provided with a curved rotating folding-blade, the edge of which presses the fold-line of the sheet against one of the folding-rolls and then moves onward with the sheet to the bite of the said rolls, 120 substantially as described.

6. The combination of the rotating blade-roll, 125 as 3, the rotating blade provided with the arm, as 42, and the cam 38, carried by one of the folding-rolls, substantially as described.

7. The combination of the rotating blade and its carrying-roll, the arm 42, the cam 38 upon one of the folding-rolls, and the train of gearing for bringing the arm 42 to the position to be caught by the cam, all substantially 130 as described.

8. The combination, with the rotating folding-blade and its shaft, of means for permitting play or lost motion between the blade and

its driving-gearing, and means for accelerating the speed of the blade during one part of its revolution, all substantially as described.

9. The combination of the folding-blade, its driving-gearing and carrying-roll, with the sleeves 16 and 17, and devices by which sleeve 17 is Jocked to the shaft or liberated and locked to sleeve 16, all substantially as described.

10. The combination, substantially as shown, of four rolls, as 46 47 56 61, provided with cutting, pasting, and folding mechanisms, whereby the web of wrapping material and the sheets to be wrapped are associated and the wrappers severed, pasted, and folded around the sheets, all substantially as described.

11. An automatic wrapping apparatus consisting of the roll 47, having the two cams 65

66, the roll 46, having the rotating folding-blade and the severing device, the roll 56, having the rotating folding-blade and the pasting device, and the roll 61, all substantially as described.

12. The combination, with the rolls 46 and 56, carrying the rotating folding-blades, as 55 25 64, of the roll 47, provided with the cams 65 66, for operating said blades, substantially as described.

In testimony whereof I have hereunto set my hand in the presence of two subscribing witnesses.

LUTHER C. CROWELL.

Witnesses:

J. A. HOVEY,
T. H. PALMER.
